UNITED STATES PATENT OFFICE.

LEWIS C. TOWER, OF ROCHESTER, NEW YORK, ASSIGNOR TO THE ELECTRIC CUTLERY COMPANY, OF NEW YORK.

RAZOR-STROP.

SPECIFICATION forming part of Letters Patent No. 412,938, dated October 15, 1889.

Application filed April 15, 1889. Serial No. 307,258. (No model.)

To all whom it may concern:

Be it known that I, LEWIS C. TOWER, of Rochester, county of Monroe, and State of New York, have invented certain new and useful 5 Improvements in Razor-Strops; and I do hereby declare the following to be a full, clear, and exact description of the same, reference being had to the accompanying drawings, forming a part of this specification, and to figures and 10 letters of reference marked thereon.

My present invention has for its object to provide an improved razor-strop that shall be cheap and simple in construction, and one which will afford an elastic stropping surface 15 or surfaces for acting upon the razor to produce the best edge for use; and to these ends it consists in certain novelties of construction and combinations of parts, all as will be hereinafter described, and the novel features 20 pointed out in the claims at the end of this specification.

In the drawings, Figure 1 is a side elevation of a strop constructed in accordance with my invention; Fig. 2, a longitudinal sectional view 25 of the same; Fig. 3, a cross-section on the line $x-x$ of Fig. 1; Fig. 4, a longitudinal sectional view of a modification; Fig. 5, a cross-section on the line $z-z$ of Fig. 4.

Similar letters of reference in the several 30 figures indicate similar parts.

The base or support of my improved strop consists of a block A, preferably of wood, provided with a handle B and on two sides with honing and stropping surfaces C and D, respectively, the former for the purpose of putting 35 an edge on a very dull razor, and the latter, of soft leather, for finishing the stropping operation.

Upon two of its sides the support A is recessed slightly, as shown, being provided at the sides with upwardly-extending ledges or flanges $a a$, while the central portions or parts between the ends are deeper, as shown at b , for the purpose of allowing the cushion-sup- 45 ports slight elastic movement, as will be described.

The stropping-cushions E are formed upon strips F, preferably of thin elastic wood, and may consist of any suitable material—such as 50 cotton or wool—contained in a suitable recep-

tacle, as a paper sheath G, secured to the strips F by glue or otherwise. The covering for the cushions, of soft leather, as usual, does not extend entirely around the strip F, but, as the sheaths containing the packing are wider 55 than the strips, passes over the outer side of said sheaths and is secured to the sides of the strip by glue or other suitable means, this arrangement economizing material. The cushion-strips F are placed in position within the 60 recesses in the base A, the ends resting upon the higher portions, while the strips are free to give slightly at the center, providing a firm elastic strop. Further, the flanges a at the side of the cushions project upward far enough 65 to protect the edges of the cushion, covering and hiding the strip-edges, thus giving a finished appearance.

While the stropping-surfaces may be secured to the base in any suitable manner by 70 attaching the ends of strips F to it, or a single stropping-cushion employed, I prefer to make the strops, as shown, with two surfaces E E'—one on each side the support for operating differently upon the razor—and in this construction make the outer leather covering of 75 them of a single piece (or sometimes two pieces of leather connected to each other at the ends, as shown) and connected to the base A at its outer end, which will hold the outer ends of 80 the strips on the base, while the ends toward the handle B may be confined and fastened by an encircling band J or in any other suitable manner. The flanges a at the sides of the base, it will be noted, also serve to sup- 85 port the edges of the stropping-cushions, should they be turned down from excessive use.

In Figs. 4 and 5 I have shown a modification, in which, instead of fastening the stropping-cushions in place by attaching their covering material to the support, I form one of the cushions at least upon a strip F in the manner described and provide on opposite sides of the ends laterally-projecting flanges 95 $f f$, arranged to co-operate with corresponding grooves or recesses in the inner sides of flanges $a a$, so that said strip will be secured at the ends, but permitted to give slightly at the middle, as before, and may be slid out when 100

desired, uncovering a recess K in the support A for the reception of a razor. A suitable button or catch L at the outer end of the support is employed to hold the cushion normally in position. This construction embodies the essential features of the other one, the cushion being formed and held and its edges protected in like manner.

The above-described strop can be very cheaply made, the amount of fine covering-leather employed being reduced to the minimum, while the finished strop is equal to any in the market, the stropping-cushions being firm and not liable to get out of shape in use, and their supports being sufficiently flexible for all purposes.

Instead of employing two stropping-cushions, as shown, one only can be employed and the construction of the cushions varied as may seem best to the constructor.

By forming the stropping-cushions upon the separate strips and afterward assembling them I am enabled to make the parts in quantities and then assemble them and complete the strops without the necessity of employing skilled labor for the latter operation.

While it is desirable to employ the stuffed cushions shown, it is not essential that they be so made, as the strips F might be covered

with soft leather, and thus answer the same purpose. Therefore by the use of the term "cushion" I do not mean to confine myself to the particular form shown.

I claim as my invention—

1. In a strop, the combination, with the base or support having the flanges or ledges at the sides, of the thin elastic strip supported thereon at the ends only, the stropping-cushion on said strip, and the covering for the same fastened to the sides below said flanges, substantially as described.

2. In a strop, the combination, with the base or support having the flanges at the sides, of the thin elastic strip supported thereon at the ends only, and the stropping-cushion on the strip projecting over the flanges on the support, substantially as described.

3. In a strop, the combination, with the base or support having the flanges at the sides, of the strip, the stropping-cushion thereon, and the covering material for the cushion secured to the strip below the flanges on the support, substantially as described.

LEWIS C. TOWER.
